WARP GOODS PROVIDED WITH RUBBER THREADS

Paul Schönfeld, Chemnitz, Germany

Application October 2, 1937, Serial No. 166,905
In Germany July 16, 1937

2 Claims. (Cl. 66—192)

This invention relates to plain warp fabric having worked in rubber threads.

Warp goods of this class with the rubber threads worked in by underlaying operations under the ground thread are known, the underlaying of the rubber threads serving for rendering the fabric elastic in both longitudinal and transverse directions. This effect is brought about by tying up the rubber threads toward the sides by the underlaying operations.

The known kinds of warp goods of this type are, however, open to the objection that they tend to roll in from the longitudinal edges, whereby further working is seriously interfered with. To overcome this trouble it has been proposed to divide the rubber warp threads into two groups and to draw them into two lapping machines which are guided in opposite directions or carry out underlaying operations differing in size. This proposal involves of course the presence of an additional lapping machine for the rubber threads, which is not an advantageous arrangement.

The invention has for its object to overcome this drawback by continually working in the rubber threads in two or more underlaying operations toward one and the same side and then back again.

One form of the invention is illustrated in the accompanying drawing wherein Figure 1 shows a lapping diagram to give a clear view of the composition of the goods, and Figure 2 shows the meshes produced by the lapping shown in Figure 1.

The warp goods comprise a ground fabric 8, filler threads 9, and the rubber threads 10. The ground fabric 8 is lapped in the form of a simple half tricot lap. The rubber threads 10 are continually worked in under the threads of the ground fabric 8 by two or more underlaying operations toward one and the same side and then back again. As shown in the drawing, the filler thread

arrangement 9 is inserted in the direction opposite to that of the ground fabric arrangement 8. To produce this fabric the threads of the ground fabric are gathered in the lower lapping machine; the filler threads 9, in the machine above; and the rubber threads 10, in the uppermost machine. The threads 9 are immaterial to the invention, they merely fill the ground fabric and could be omitted, in which case the rubber threads 10 would be drawn into the machine disposed above the machine for the threads of the ground fabric.

The ground fabric may of course be lapped differently than shown. Similarly, the rubber threads 10 can be lapped in some other way, for instance by underlaying them each under 2.

It is further immaterial how many rubber threads are placed in the goods, and the lapping of the filler threads may be different also. The numbers 1 to 6 indicate the courses in which the racking of the rubber warp threads 9 is repeated.

It should be noted that the upper lapping machine is the one which is directed toward the needles when the machines are situated upon that side of the needles from which the goods are removed.

I claim:

1. Plain knit warp goods provided with rubber warp threads worked in by underlaying operations and under the ground thread arrangement, wherein the rubber threads are continually worked in by two or more underlaying operations toward one and the same side and then back again.

2. Plain knit warp goods in accordance with claim 1, wherein a filler thread arrangement is situated between the ground thread arrangement and the rubber thread arrangement, said filler thread arrangement being inserted opposite the ground thread arrangement.

PAUL SCHÖNFEILD.
